HENRY A. WISE WOOD, OF NEW YORK, N. Y., ASSIGNEE TO WOOD NEWSPAPER MACHINERY CORPORATION, OF NEW YORK, N. Y., A CORPORATION OF VIRGINIA.

ELECTRICALLY OPERATED METAL PUMP

Application filed December 18, 1926, Serial No. 155,627. Renewed April 15, 1930.

This invention relates to a pump for molten metal particularly adapted for filling molds for casting stereotype printing plates. Heretofore the pumping of the molten metal was done by a hand lever and it required the lifting of a weight of metal equal to the weight of the cast plate and its tail, together with a surplus for safety. This metal was lifted to a considerable height by a single stroke of the handle. This invention is designed to avoid the necessity of lifting such a weight of metal by hand for each cast.

The principal objects of this invention are to provide power operated means for accomplishing the heavy work of lifting the metal and to provide a single control for starting the electric motor which is used and providing for the proper operation of the pump, and also automatic means for stopping the motor at the right time. More specifically, the invention involves means whereby a single movement of the control handle in one direction starts the motor and closes the by-pass in the pump, so that the metal will flow into the mold and means whereby, when the control handle is reversed, the by-pass is first opened, permitting the excess metal to return to the pot without stopping the pump, and the motor will continue to run until the main shaft has made a complete revolution, at which point the power is shut off automatically.

Other objects and advantages of the invention will appear hereinafter.

Reference is to be had to the accompanying drawings in which

Fig. 1 is a plan of a pump constructed in accordance with this invention;

Fig. 2 is a sectional view of the pump proper on the line 2-2 of Fig. 1, showing the parts above in elevation;

Fig. 3 is a side elevation looking in the direction of the arrow 3 in Fig. 1 with the by-pass of the pump shown in section; and

Fig. 4 is a fragmentary view similar to Fig. 3 with parts broken away and showing the switch closed and the parts in operation.

In the form shown in the drawings, the furnace casing 1 is used as usual to support

the melting pot 2 in which is located the pump casing or barrel 3. The pump casing is supported on an integrally cast bracket 4 carried on the top of the furnace. On this bracket also is carried an electric motor 5 which by means of a chain 6 and sprocket wheels transmits the power to a shaft 7 at a reduced speed. This shaft is shown horizontally located and carried on the bracket 4 and is provided with a worm 8 meshing with a worm wheel 9 on a transverse shaft 10. On the worm wheel is a stud 11 located eccentrically and operating a link 12. This link is connected by a stud 13 with a piston rod 14 which slides in bearings 15 and 16. On the piston rod is a piston 17 working in the pump barrel 3 which, when lifted, forces the charge of metal up the spout 18 and into the mold.

On the sprocket wheel 9 is a hub provided with a depression 20. On a horizontal shaft 21 is loosely pivoted an arm 22 having a roller 23 rolling on the surface of the hub. When this hub turns around to a position for the depression 20 to receive the roller 23, this arm 21 is free to fall back into the position shown in Fig. 3. Fixed on this shaft 21 is another arm 25 which at the end carries a rod 26 operating the by-pass valve 27. This lowers the by-pass valve so that the metal raised by the piston 17 will flow into the pot directly without ever going into the spout 18. It will be seen therefore that the pump can operate through a part of a stroke without delivering any metal.

Fixed on the arm 22 is a projection 22a provided with a rod 27a which is connected with a switch 28 to open and close it in accordance with the position of the arm 22 and as shown in Figs. 3 and 4. It will be seen from these figures that the switch which supplies the current to the motor is closed when the roll 23 is on the high part of the hub cam and will be opened as stated above when the roller 23 is in the depression 20. At the same time the by-pass valve 27 is opened and the pump is inoperative for the time being.

This is all controlled by the shaft 21 which is provided with an operating handle 28a. The shaft 21 is mounted to turn in bearings 24.

A spring 29 is free on the shaft 21 but one end is held in one of the bearings 24 and the other in the arm 22. The spring is coiled so as to hold this arm inwardly so that the roller 23 will roll on the surface of the hub of the gear 9. The pin or stud 31 is carried by the arm 22 and the arm 30 is fixed on the shaft 21. The spring 29 holds the arm 22 against the hub cam at all times so that the roller will always fall into the notch or depression 20 when it comes around.

In the operation of the device, assuming the parts to be at rest as shown in Figs. 1, 2 and 3 the operator turns the handle 28a to move the rod 21 back to the position shown in Fig. 4 and positively swings the arm 30, which through the stud 31, draws the arm 22 back positively and closes the switch. This starts the motor and also raises the rod 26 to close the valve 27 so that the pump is put into operative position. The rotation of the parts by the motor causes the link 12 of course, to move around from the position shown in Fig. 3 to the same position again, giving one full stroke to the pump piston and filling the mold. It will be noted that the movement of the handle 28a in this direction positively operates the shaft 21 but, when the handle 28a is turned back to the original position, it opens the by-pass valve 27 but it does not disengage the switch 28. It merely permits the spring 29 to perform that function, whenever the cam rotates around to bring the notch 20 into registration with the roller 23. Therefore the pump continues throughout its full stroke, although the by-pass is opened. The breaking of the current feeding the motor of course is not accomplished until the worm wheel 9 is rotated around again to the original position shown in Fig. 3 which completes its rotation. This causes the roller 23 to fall into the notch 20 which is the cam that opens the switch and stops the motor. The operator can turn the handle 28a back when the mold is filled and leave the machine to continue its operation and come to a stop.

It will be seen therefore that the heavy work of lifting metal is accomplished by power and yet the operator has full control of the time of starting the motor and also the time of stopping the effective operation of the pump, but he does not stop by hand the motion of the piston. That is stopped automatically with the piston down in the position shown in Fig. 2 and with the parts in the proper position for starting again to perform a complete operation.

Although I have illustrated and described only a single form of the invention I am aware of the fact that modifications can be made therein by any person skilled in the art without departing from the scope of the invention as expressed in the claims.

Therefore, I do not wish to be limited to

all the details of construction herein shown and described, but what I do claim is:—

1. In a stereotype plate metal pump, the combination with the pump, its piston and a by pass valve which, when opened, prevents the pump from forcing metal up the spout thereof, of power operated means for lifting the piston to discharge metal, of a switch for controlling said power operated means, hand-operated means for closing said switch and opening the by-pass, and automatic means for thereafter throwing off the power when the piston has made a complete stroke in both directions.

2. In a mold filling pump, the combination with a pump barrel and its piston, of an electric motor, means connected with the electric motor for reciprocating the piston, a shaft having a handle for controlling the machine, a switch for controlling the supply of power to the motor, means tending to open the switch, and means operated by the piston reciprocating means to hold the switch closed until the pump piston has made a complete reciprocation.

3. In a mold filling pump, the combination with a pump barrel and its piston, of an electric motor, means connected with the electric motor for reciprocating the piston, a shaft having a handle for controlling the machine, means on the shaft for controlling the operativeness of the pump at the will of the operator, a pivoted arm, a spring for normally forcing the arm in one direction, a switch for controlling the supply of power to the motor, means on said arm tending to open the switch when the spring is allowed to act, and means operated by the piston reciprocating means for keeping the arm in a position to hold the switch closed until the pump piston has made a complete reciprocation.

4. In a mold filling pump, the combination with a pump barrel and its piston, of a motor, a wheel connected with the motor to be rotated thereby, connections between the wheel and the pump piston for reciprocating the piston once for each rotation of the wheel, a switch for supplying the motor with power, means connected with said wheel for holding said switch closed throughout a rotation of the wheel and then allowing it to be opened at the end of the rotation when the piston is down, and spring-pressed means for opening the switch when allowed to do so.

5. In a pump for filling molds with molten metal, the combination with the pump barrel, a piston therein, and a by-pass having a valve which, when opened, permits the metal to flow out of the barrel without entering the mold, of a control shaft adapted to be turned to two positions, means fixed on the control shaft for closing the by-pass valve, an electric motor, means operated by the motor for reciprocating the piston of the pump, a switch for controlling the operation of the motor,

and means whereby when the piston has made a complete reciprocation in both directions the switch will be thrown out automatically, irrespective of the position of said handle, whereby the handle can be turned to open the by-pass before the motor is stopped.

6. In a mold filling pump, the combination with the pump barrel, its piston, an electric motor for operating the piston and a motor switch, of a by-pass valve in the pump barrel, a hand control shaft, means fixed on the shaft for operating the by-pass valve, a spring coiled on the shaft and fixed at one end, an arm loose on the shaft and connected with the other end of the spring, said arm being provided with means for opening and closing the motor switch and the spring being set to tend to move the arm in a direction to open the switch, means fixed on the control shaft for holding said arm back against the action of the spring until the controlling shaft is turned to allow the switch to be opened.

7. In a mold filling pump, the combination with the pump barrel, its piston, an electric motor for operating the piston and a motor switch, of a by-pass valve in the pump barrel, a hand control shaft, means fixed on the shaft for operating the by-pass valve, a spring coiled on the shaft and fixed at one end, an arm loose on the shaft and connected with the other end of the spring, said arm being provided with means for opening and closing the motor switch and the spring being set to tend to move the arm in a direction to open the switch, means fixed on the control shaft for holding said arm back against the action of the spring until the controlling shaft is turned to allow the switch to be opened, and means operated by the motor for controlling the closing of the switch so that it can be opened only when the pump piston is substantially at the end of its stroke.

8. In a mold filling pump, the combination with the pump barrel, its piston, an electric motor for operating the piston and a motor switch, of a hand control shaft, a spring coiled on the shaft and fixed at one end, an arm loose on the shaft and connected with the other end of the spring, said arm being provided with means for opening and closing the motor switch and the spring being set to tend to move the arm in a direction to open the switch, and means operated by the motor for controlling the closing of the switch so that it can be opened only when the pump piston is substantially at the end of its stroke.

9. In a pump, the combination with the piston and a by pass valve which, when opened, prevents the pump from forcing metal up the spout thereof, of power operated means for lifting the piston to discharge metal, a switch for controlling said power operated means, and a hand operated means for both closing said switch and opening the by-pass.

10. In a mold filling pump, the combination with a pump barrel and its piston, of means for reciprocating the piston, a switch for controlling the supply of power to the piston reciprocating means, means tending to open the switch, and means operated by the piston reciprocating means to hold the switch closed until the pump piston has made a complete reciprocation.

11. In a pump, the combination with a melting pot, a piston and cylinder, a motor and means by which the motor operates the piston, the cylinder having a by-pass, of a control handle, means whereby a single movement of the control handle in one direction starts the motor and closes the by-pass so that the metal will flow and means whereby, when the control handle is reversed, the by-pass is first opened, permitting the excess metal to return to the pot without stopping the pump, and the motor will continue to run until the pump has made a complete cycle of operations at which point the power is shut off automatically.

In testimony whereof I have hereunto affixed my signature.

HENRY A. WISE WOOD.
